UNITED STATES PATENT OFFICE

NILS D. LEVIN, OF COLUMBUS, OHIO, ASSIGNOR TO THE JEFFREY MANUFACTURING COMPANY, OF COLUMBUS, OHIO, A CORPORATION OF OHIO

COAL CUTTING MACHINE

Application filed November 1, 1928, Serial No. 316,584. Renewed April 10, 1931.

The present invention relates to certain new and useful improvements in coal cutting machines and particularly to machines of the class comprising a frame adapted to 5 rest upon and slide in any direction over the mine floor, a kerf cutter projecting horizontally therefrom, winding devices mounted upon the main frame and flexible draft devices attached to and windable upon said 10 winding devices adapted to cooperate with anchoring devices external of the machine to move and guide it relative to the material to be mined.

It is the especial object of this invention 15 to provide, in a machine of the class described, an improved arrangement of parts whereby the external dimensions of the machine may be reduced without impairment of the efficiency, strength or durability of the 20 machine.

A further object is to provide improved feeding and guiding mechanism of extreme 25 simplicity of design and efficiency of operation.

25 A further object is to provide improved controlling mechanism for said feeding and guiding mechanism.

The means whereby I attain these objects 30 are fully set forth in the following specification and illustrated in the accompanying drawings of which

Fig. 1 is a plan view of the preferred embodiment of my invention.

Fig. 2 is a side elevation of the machine 35 illustrated in Fig. 1.

Fig. 3 is a sectional view taken along the line III—III of Fig. 1.

Fig. 4 is a fragmentary plan view of the 40 rearward part of the machine illustrated in Figs. 1 and 2, certain parts being removed to reveal the parts below.

Fig. 5 is a sectional view taken along the line V—V of Fig. 4.

Fig. 6 is a detail of the actuating mechanism of the feed rope winding drum.

Fig. 7 is a sectional view taken along the line VII—VII of Fig. 4.

Fig. 8 is a sectional view taken along the 50 line VIII—VIII of Fig. 4.

Figs. 9 and 10 and 11 are diagrams illustrating methods of operating the machine.

Like numerals refer to similar parts in the several figures.

In the drawings the numerals 1, 2 and 3 refer to three steel castings which are securely bolted together to form a main frame. The lower portion of middle section 2 rests directly on the mine floor, while the front and rear sections 1 and 3 comprise hollow portions or frame elements 1a and 3a which are spaced above relatively thin shoes or pans 1b and 3b which support the ends of the machine on the mine floor. The shoe 1b, portion 3a, and shoe 3b are in tongue and groove connection with the middle section as indicated at 1c, 3c, and 3d respectively. The middle section 2 is shaped to form the magnetic field frame of an electric motor by which the operative parts of the machine are actuated, and these parts are so proportioned and arranged that the height of the motor frame substantially limits the vertical dimensions of the machine. Within the magnetic field frame thus provided there is mounted an armature 4 which extends longitudinally of the machine and is supported in suitable bearings not shown in the drawings. The motor above described is provided with suitable electric controlling devices and is connectible through any suitable and convenient means with a source of electric current supply, but as such devices are well understood in the mining machine art, and as they form no part in the present invention their illustration and description is not thought to be required at this time.

The forward frame section 1 is shaped to form the journal bearing 5 wherein is rotatably supported the vertical shaft 6. Mounted concentrically with the shaft 6 and freely rotatable thereto is a bevel gear 7 having a hub 8 the outer surface of which is journaled in a bearing 9 of the extension frame 1. Within the hub 8 of the gear 7 is formed a journal bearing 10 wherein is rotatably supported the upper end of the shaft 6. The bevel gear 7 meshes with a bevel pinion 11 (shown by dotted lines in Fig. 1 of the drawings) fixed to the armature shaft 100

4 of the motor whereby the gear 7 is rotated about its axis.

Slidably mounted upon the shaft 6 and rotatably connected thereto by a suitable feather key, is a clutch member 12 having clutch teeth 13 adapted to engage corresponding teeth 14 formed on a gear member 25. The clutch member 12 is engaged by a clutch collar 15 which is connected with a shifting lever 16 supported upon the pivot pin 17 of the extension frame. This lever 16 is adapted to be oscillated about said pivot pin by an eccentric 18 fixed to the shaft 19 journaled in suitable bearings of the extension frame. At its outer end the shaft 19 is pierced by a suitable aperture through which extends the operating handle 20 which is longitudinally slidably transversely of the shaft 19. These parts are so proportioned and arranged that by manipulation of the handle 20 the shaft 19 may be rotated to cause the eccentric 18 to oscillate the lever 16 and thereby shift the clutch member 12 into or out of engagement with the gear member 7. The handle 20 is also adapted to be placed in such engagement with a flange 21 of the extension frame that it will hold these parts in the desired relation.

Keyed to the shaft 6 is a sprocket wheel 22 which engages the cutter chain 23. The chain 23 is adapted to travel in guideways formed on the lateral edges of the cutter arm 24 which projects horizontally from the extension frame 1 in the manner which is well understood in the mining machine art. The spacing of the side runs of the chain, Figure 3, is such as to bring them within the lateral edges of the shoe 1b so that in shoveling slack at the head of the machine, the shovel will strike the shoe instead of the bits.

Fixed to the bevel gear 7 concentric therewith is a bevel gear 25 which engages a similar gear 26 keyed to the horizontal shaft 27 journaled in suitable bearings of the extension frame 1. Formed integral with the shaft 27 is a segmental flange 28 having a surface 29 adapted to engage a suitable clutch member 30 formed integral with a hub member 31. The hub member 31 is longitudinally slidable upon the shaft 27 so that the clutch member 30 may be placed in or removed from operative relation from the flange 28. Two spaced apart annular grooves 32 and 33 formed in the hub member 31 are adapted to be engaged by a detent pin 34 to hold these parts in the desired relation to each other. Formed on the outer end of the hub 31 is a sprocket wheel 35 adapted to be engaged by a suitable endless chain whereby rotative power may be transmitted from the mining machine motor to the axles of a supporting truck when the mining machine is loaded thereon, to propel said truck along the rails of the mine track.

Within the rearward section 3 of the machine frame is supported the feeding and

guiding mechanism which comprises two winding drums 36 and 37 symmetrically placed on either side of the longitudinal center line of the machine directly above shoe 3b, and upon these drums are windable the flexible draft elements 38 and 39, preferably wire rope, adapted to be secured to anchoring devices external of the machine. The drums 36 and 37 are substantially alike and each is journaled upon a hub 40 which is eccentrically rotatable about a fixed vertical pin 41. The ends of pins 41, as in Figure 7, are reduced, forming shoulders resting against the lower wall of portion 3a and shoe 3b. The reduced ends are threaded and nuts are screwed thereon above the wall and beneath the shoe. Pins 41 are thus adapted to take both tensile and compressive strains. Formed integral with each of the hubs 40 is a lever 42 whereby said hubs may be rotated to move the central axis of the respective drums relative to the vertical shafts 43 and 44 which are journaled in the frame portion 3a with their lower ends projecting freely therebelow. A pin 45 adapted to engage registering apertures in the frame casting and in each of the levers 42 serves to lock the hubs in the preferred position of angular adjustment. Each of the drums 36 and 37 is provided with a bottom web and with internal gear teeth adapted to engage the teeth of the pinions 46 and 47 which are formed integral with the shafts 43 and 44 on their downwardly projecting ends. The proportions and arrangement of these parts are such that by movement of the lever 42 the internal gear teeth of the drums may be brought into engagement with said pinions to rotate said drums in a direction to wind the ropes, or may be moved out of such engagement to permit their free rotation in the unwinding direction.

Mounted concentrically with the shaft 43 within the frame portion 3a is a worm gear 48 which engages a worm 49 formed integral with the extension 50 of the armature shaft 4 of the motor. The worm gear 48 is fixed to the driving member 51 of a multiple disc friction clutch the driven member 52 of which is fixed to the shaft 43. These clutch members are adapted to be operatively connected by the clutch discs 53 when pressure is applied thereto through the pressure pins 54. The pins 54 are attached to a collar 55 adapted to be engaged by a thrust collar 56 screw threaded upon the outer surface of the journal bearing 57 in which the upper end of the shaft 43 is supported. The arrangement of these parts is such that rotation of the thrust collar 56 in one direction screws said collar downwardly to exert pressure upon the pins 54, while its rotation in the opposite direction screws said collar upwardly to relieve that pressure.

Formed integral with the thrust collar 56

is a sprocket wheel 58 around which passes an endless chain 59 whereby said thrust collar is operatively connected with the sprocket wheel 60 fixed to a vertical shaft 61 journaled in 5 suitable bearings of the machine frame. The shaft 61 is connected with a horizontal shaft 62 by a pair of mitre gears 63 and 64, and to the shaft 62 is fixed a hand wheel 65, positioned convenient to the hand of the operator. 10 By manipulation of the hand wheel 65 the thrust collar 56 may be rotated to control the actuation of the friction clutch and thereby control the rotation of the winding drum 36.

Keyed to the shaft 44 is the driven member 15 66 of a multiple disc friction clutch the driving member 67 of which is rotatably mounted upon the hub 68 of said driven member. These clutch members are adapted to be operatively connected together by a plurality of friction discs 69 when said discs are pressed together by the pressure pins 70. The pins 70 are attached to a ring 71 adapted to be engaged by a thrust collar 72 screw threaded to the outer surface of the journal bearing 73 20 in which the upper end of the shaft 44 is supported. Formed integral with the thrust collar 72 is a sprocket wheel 74 around which passes an endless chain 75 by which said thrust collar is operatively connected with a 25 sprocket wheel 76 fixed to a vertical shaft 77 supported in suitable bearings of the machine frame. The vertical shaft 77 is connected with the horizontal shaft 78 by suitable mitre gears, and to this horizontal shaft 78 is fixed a hand wheel 79 positioned convenient to the 30 hand of the operator. By manipulation of the hand wheel 79 the thrust collar 72 may be rotated in one direction to screw it downwardly to apply pressure upon the disc 69 to 35 connect the driving member 67 with the shaft 44, or it may be rotated in the opposite direction to screw said collar upwardly to relieve 40 that pressure.

An eccentric 80 formed integral with the 45 driving clutch member 51, and thereby fixed to the worm gear 48, is engaged by an eccentric strap 81. An eccentric rod 82 formed integral with the eccentric strap 81 is connected by a suitable wrist pin 83 with the projecting flange 84 of a ring 85 mounted upon the periphery of the clutch member 66 for free rotation relative thereto. A pawl 86 pivotally mounted upon the wrist pin 83 engages the ratchet 87 formed integral with the driving 50 clutch member 67. By the oscillating engagement of the pawl 86 with the ratchet 87 rotary motion is imparted to the clutch member 67 to drive the shaft 44. Pivotally attached to the eccentric strap 81 by a wrist pin 88 is a connecting rod 89 the other end of which is attached by a wrist pin 90 with the projecting flange 91 of a second ring 92 mounted upon the clutch member 66. Mounted upon the flange 91 is a second pawl 93 arranged to engage 55 the ratchet 87 in such manner that the

two pawls 86 and 93 act alternately to produce substantially continuous rotation of the shaft 44. A third pawl 94 mounted upon the frame of the machine acts to prevent retrograde movement of the ratchet 87. 70

Surrounding the ratchet 87 and concentric therewith is a circular shield 95 having suitable openings through which the pawls 86, 93 and 94 may project to engage the ratchet 87. This shield 95 is rotatably adjustable about the axis of the ratchet and controls the engagement of the pawls 86 and 93 therewith thereby regulating the rate of rotation of the shaft 44. An arm 96 projecting from the shield 95 carries a spring 80 pressed detent 97 adapted to engage either of a plurality of apertures in a segmental flange 98 of the machine frame to hold the shield 95 in the preferred position of adjustment about its axis. Such ratchet controlling mechanism is fully illustrated and described in my Patent No. 1,247,419, and a more complete disclosure at this time is not thought to be required. 85

In the customary method of operation the 90 cutter bar 24 is first thrust longitudinally into the coal body to make the sumping, or entering cut, after which the machine is moved laterally across the coal face to form 95 a kerf therein.

To make the sumping cut the machine is positioned upon the mine floor with the cutter arm 24 projecting into the corner of the mine room, as illustrated in Fig. 9. The levers 42 are then moved to disengage the 100 pinions 46 and 47 from the internal gears of the drums 36 and 37. The ropes 38 and 39 may then be drawn out from their respective drums and their free ends attached to the anchor jacks 99 and 100 which are suitably placed adjacent the coal face 101. Guide rollers 102 and 103 are mounted at the forward corners of the machine frame to engage the feed ropes and prevent their chafing 105 against the corners of the frame casting. After the ropes 38 and 39 are suitably anchored the levers 42 are again moved to restore engagement of the pinions 46 and 47 with the drums 36 and 37. When now the 110 cutter chain is actuated manipulation of the hand wheels 65 and 79 will cause engagement of the friction clutches to simultaneously actuate both winding drums to wind their respective ropes and thereby draw the machine bodily longitudinally forward to force the cutter bar 24 into the coal. The direction of movement of the cutter arm may be controlled by manipulation of one or other of the hand wheels 65 or 79 to permit more or less slippage in one or other of the friction 115 clutches.

After the cutter arm 24 has been fully sumped, the rope 39 may be disconnected from the anchor jack 100, passed around the guide roller 103 and secured to an 120 125 130

anchor jack 104 positioned at the left hand rib adjacent the coal face 101, as shown in Fig. 10. The rope 38 may be disconnected from the anchor jack 99 and attached to an anchor jack 105 positioned adjacent the right hand rib at a suitable distance from the face 101. When so arranged the hand wheel 79 may be manipulated to actuate the drum 37 to draw the machine toward the left hand rib, and the hand wheel 65 manipulated to permit the unwinding of the rope 38 from the drum 36 under frictional resistance to maintain the balance of forces and thereby hold the machine in the desired angular relation to the coal face.

A preferred arrangement for operating the machine from left to right is shown in Figure 11. According to this figure, the cutter bits are reversed in their sockets and the motor is reversed to give the chain the proper direction of movement. Reversal of the motor will cause reversal in the direction of rotation of drum 36, but in view of the pawl and ratchet connections between this drum and the feed drum 37, the latter will be rotated in the same direction as when the motor is rotating in normal direction. That is to say, drum 37 is capable only of unidirectional rotation, regardless of the direction of rotation of the motor.

It will be noted from Figure 1, as well as from Figure 11, that a bollard 110 is positioned immediately in front of drum 36, this bollard being of the same form as that shown at 112, Figure 2. As shown in Figure 11, feed rope 39 is passed around bollard 110 between the latter and drum 36, carried forward around sheave 102 and secured to a suitable anchor jack 113 at the right hand rib. Rope 38 is entirely unwound from drum 36 and rewound thereon in the opposite direction. Its free end is passed in contact with sheave 111, Figures 1, 2 and 11, and secured to a suitably disposed anchor jack 114. The manipulation of the machine with the elements in the described arrangement, will be controlled in exactly the same manner as has been described in connection with Figure 10.

It is to be understood that I do not limit myself to the precise construction or to the manipulations here illustrated and described, as the mechanism may be subject to wide variation as to detail without departure from the spirit of my invention.

What I claim is:

1. In a machine of the class described, the combination with a frame, of a motor mounted thereon, a shaft rotatably mounted upon said frame, devices adapted to transmit rotative power from said motor to said shaft including a friction clutch, a thrust collar screw threaded to an element of said frame adapted to cause engagement of the friction elements of said clutch, a sprocket wheel on

said collar, an endless chain engaging said sprocket wheel, and means to actuate said chain to rotate said collar and thereby control the actuation of said clutch as and for the purpose set forth. 70

2. In a machine of the class described, the combination with a frame, of a motor mounted thereon, a shaft rotatably mounted upon said frame, devices adapted to transmit rotative power from said motor to said shaft including a friction clutch mounted coaxially with said shaft, a thrust collar screw threaded to an element of said frame adapted to cause engagement of the friction elements of said clutch, a sprocket wheel on said collar, an endless chain engaging said sprocket wheel, and means to actuate said chain to rotate said collar and thereby control the actuation of said clutch as and for the purpose set forth. 75

3. In a machine of the class described, the combination with a frame, of a motor mounted thereon, a shaft rotatably mounted on said frame, devices adapted to transmit rotative power from said motor to said shaft including a friction clutch, a thrust collar screw threaded to an element of said frame adapted to cause engagement of the friction elements of said clutch, a sprocket wheel on said collar, an endless chain engaging said sprocket wheel, and manually actuated means to actuate said chain to rotate said collar and thereby control the actuation of said clutch as and for the purpose set forth. 80

4. In a machine of the class described, the combination with a frame, of a motor mounted thereon, a shaft rotatably mounted on said frame, devices adapted to transmit rotative power from said motor to said shaft including a friction clutch mounted coaxially with said shaft, a threaded sleeve on the frame coaxial with said shaft, a screw threaded thrust collar engaged on said threaded sleeve and displaceable therealong upon rotation in opposite directions to cause the engagement of the friction elements of said clutch, a sprocket wheel on said thrust collar, an endless chain engaging said sprocket wheel, and means to actuate said chain to rotate said collar and thereby control the actuation of said friction clutch as and for the purpose set forth. 100

5. In a machine of the class described, the combination with a frame adapted to rest upon and slide in any direction over the floor of a mine, of a kerf cutter projecting horizontally therefrom, feeding and guiding mechanism comprising two flexible draft elements adapted to cooperate with anchoring devices external of the machine, two winding drums rotatably mounted upon the frame on parallel axes adapted to wind said draft elements, continuously acting power transmission devices including a drum engaging shaft and a coaxial rotary member adapted to transmit rotative power from said motor 105

to one of said drums, a separate drive shaft engaged with the other drum and power transmitting devices including intermittently acting means adapted to transmit rotative power from said rotary member to said last named drum driving shaft as and for the purpose set forth.

6. In a machine of the class described, the combination with a frame adapted to rest upon and slide in any direction over the floor of a mine, of a kerf cutter projecting horizontally therefrom, feeding and guiding mechanism comprising two flexible draft elements adapted to cooperate with anchoring devices external of the machine, two winding drums rotatably mounted upon the frame on parallel axes adapted to wind said draft elements, continuously acting power transmitting devices including a drum engaging shaft and a coaxial rotary member adapted to transmit rotative power from said motor to one of said drums, friction devices interposed between said rotary member and said shaft adapted to control the winding and unwinding of said draft element by said one of the drums, and a separate driving shaft engaged with the other drum and power transmitting devices including intermittently acting means adapted to transmit rotative power from said rotary member to said last named drum driving shaft as and for the purpose set forth.

7. In a machine of the class described, the combination with a frame adapted to rest upon and slide in any direction over the floor of a mine, of a kerf cutter projecting horizontally therefrom, feeding and guiding mechanism comprising two flexible draft elements adapted to cooperate with anchoring devices external of the machine, two winding drums rotatably mounted upon said frame adapted to wind said draft elements, continuously acting power transmission devices adapted to transmit rotative power from said motor to one of said drums, intermittently acting constant direction power transmission devices adapted to transmit rotative power to the other drum, and friction devices interposed between said transmission devices and said drums to control the winding and unwinding of said draft elements as and for the purpose set forth.

8. In a machine of the class described, the combination with a frame adapted to rest upon and slide in any direction over the floor of a mine, of a kerf cutter projecting horizontally therefrom, feeding and guiding mechanism comprising two flexible draft elements adapted to cooperate with anchoring devices external of the machine, two winding drums rotatably mounted upon the frame adapted to wind said draft elements, continuously acting power transmission devices adapted to transmit rotative power from said motor to one of said drums, intermittently

tently acting constant direction power transmitting devices adapted to transmit rotative power to the other drum, and means to permit the unwinding of said draft elements as and for the purpose set forth.

9. In a machine of the class described, the combination with a frame adapted to rest upon and slide in any direction over the floor of a mine, of a kerf cutter projecting horizontally therefrom, feeding and guiding mechanism comprising two flexible draft elements adapted to cooperate with anchoring devices external of the machine, two winding drums rotatably mounted upon the frame adapted to wind said draft element, continuously acting power transmission devices adapted to transmit rotative power from said motor to one of said drums, intermittently acting power transmission devices adapted to transmit rotative power to the other drum, friction devices interposed between said transmission devices and said drums to control the winding and unwinding of said draft elements, and means to permit the free unwinding of said draft elements as and for the purpose set forth.

10. In a machine of the class described, the combination with a frame adapted to rest upon and slide in any direction over the floor of a mine, a kerf cutter projecting horizontally therefrom, a motor mounted upon said frame and connected with said kerf cutter, feeding and guiding mechanism comprising two flexible draft elements adapted to cooperate with anchoring devices external of the machine, two winding drums rotatably mounted on said frame and adapted to wind said draft elements, gearing arranged to transmit rotative power from said motor to one of said drums, a friction clutch interposed between said gearing and said drum, means to actuate said friction clutch to control the winding and unwinding of the draft element, and ratchet mechanism adapted to transmit rotative power to the other drum as and for the purpose set forth.

11. In a machine of the class described, the combination with a frame adapted to rest upon and slide in any direction over the floor of a mine, a kerf cutter projecting horizontally therefrom, a motor mounted on said frame and connected with said kerf cutter, feeding and guiding mechanism comprising two flexible draft elements adapted to cooperate with anchoring devices external of the machine, two winding drums rotatably mounted on said frame adapted to wind said draft elements, gearing arranged to transmit rotative power from said motor to one of said drums, ratchet mechanism adapted to transmit rotative power to the other drum, friction clutches interposed between said transmission devices and said drums, and manually actuated means to control said friction clutches to control the winding and unwinding of said

flexible draft elements as and for the purpose set forth.

12. In a mining machine, the combination with a supporting frame adapted to rest upon and slide in any direction over the floor of a mine, a motor mounted thereon, mining mechanism carried by said frame and actuated by said motor, feeding and guiding mechanism including two flexible draft elements adapted to cooperate with anchoring devices external of the machine, two winding drums rotatably mounted upon said frame on which said draft elements are windable, gearing arranged to transmit rotative power from said motor to one of said drums, and ratchet mechanism adapted to transmit rotative power to the other drum as and for the purpose set forth.

13. In a mining machine, the combination with a frame adapted to rest upon and slide in any direction over the floor of a mine, a motor mounted thereon, mining mechanism carried by said frame and actuated by said motor, feeding and guiding mechanism including two flexible draft elements adapted to cooperate with anchoring devices external of the machine, two winding drums rotatably mounted upon said frame on which said draft elements are windable, worm gearing arranged to transmit rotative power from said motor to one of said drums, and ratchet mechanism adapted to transmit rotative power to the other drum as and for the purpose set forth.

14. In a mining machine, the combination with a frame adapted to rest upon and slide in any direction over the floor of a mine, a motor mounted thereon, mining mechanism carried by said frame and actuated by said motor, feeding and guiding mechanism including two flexible draft elements adapted to cooperate with anchoring devices external of the machine, two winding drums rotatably mounted on said frame on which said draft elements are windable, worm gearing arranged to transmit rotative power from said motor to one of said drums, and ratchet mechanism adapted to transmit rotative power to the other drum as and for the purpose set forth.

15. In a mining machine, the combination with a frame adapted to rest upon and slide in any direction over the floor of a mine, a motor mounted thereon, mining mechanism carried by said frame and actuated by said motor, feeding and guiding mechanism including two flexible draft elements adapted to cooperate with anchoring devices external of the machine, two winding drums rotatably mounted upon said frame on which said draft elements are windable, worm gearing arranged to transmit rotative power from said motor to one of said drums, and ratchet mechanism actuated by said worm gearing adapted to transmit rotative power to the other drum as and for the purpose set forth.

16. In a machine of the class described, the combination with a frame adapted to rest upon and slide in any direction over the floor of a mine, of a kerf cutter projecting horizontally therefrom, a motor mounted upon said frame, feeding and guiding mechanism comprising two shafts rotatably mounted on said frame, gearing including a friction clutch adapted to transmit rotative power from said motor to one of said shafts, ratchet mechanism actuated by said gearing, a friction clutch arranged to connect said ratchet mechanism with the other shaft to rotate it, a winding drum connectible with each of said shafts, and flexible draft elements windable upon said drums adapted to cooperate with anchoring devices external of the machine as and for the purpose set forth.

17. In a machine of the class described, the combination with a frame adapted to rest upon and slide in any direction over the floor of a mine, a kerf cutter projecting horizontally therefrom, feeding and guiding mechanism comprising two flexible draft elements adapted to cooperate with anchoring devices external of the machine, two winding drums rotatably mounted on vertical axes upon said frame and adapted to wind said draft elements, means to cause the rotation of one of said drums in either direction, and means to cause simultaneous rotation of the other drum in a winding direction as and for the purpose set forth.

18. In a machine of the class described, the combination with a frame adapted to rest upon and slide in any direction over the floor of a mine, a kerf cutter projecting horizontally therefrom, a motor mounted upon said frame, feeding and guiding mechanism comprising two flexible draft elements adapted to cooperate with anchoring devices external of the machine, two winding drums rotatably mounted on vertical axes upon said frame and adapted to wind said draft elements, means to connect one of said drums with said motor to cause its rotation in a direction depending upon the direction of rotation of the armature of the motor, and means to connect the other drum with the motor to cause its simultaneous rotation in a winding direction regardless of the direction of motor rotation as and for the purpose set forth.

19. In a machine of the class described, the combination with a frame adapted to rest upon and slide in any direction over the floor of a mine, of a kerf cutter projecting horizontally therefrom, feeding and guiding mechanism comprising two flexible draft elements adapted to cooperate with anchoring devices external of the machine, two winding drums rotatably mounted upon spaced apart vertical axes symmetrically disposed upon said frame and adapted to wind said draft elements, means to cause rotation of one of said drums in a winding direction and

means to simultaneously cause rotation of the other drum in an unwinding direction as and for the purpose set forth.

20. In a machine of the class described, the combination with a frame adapted to rest upon and slide in any direction over the floor of a mine, of a kerf cutter projecting horizontally therefrom, feeding and guiding mechanism comprising two flexible draft elements adapted to cooperate with anchoring devices external of the machine, two winding drums rotatably mounted on spaced apart vertical axes symmetrically disposed in a plane extending transversely of the machine and adapted to wind said draft elements, means to cause rotation of one of said drums in a winding direction and means to simultaneously cause rotation of the other drum in an unwinding direction as and for the purpose set forth.

21. In a machine of the class described, the combination with a frame adapted to rest upon and slide in any direction over the floor of a mine, a kerf cutter projecting horizontally therefrom, a motor mounted upon said frame connected with said kerf cutter, feeding and guiding mechanism comprising two flexible draft elements adapted to cooperate with anchoring devices external of the machine, two winding drums rotatably mounted upon said frame adapted to wind said draft elements, power transmitting devices including friction clutches adapted to transmit rotative power from said motor to said drums, thrust collars screw threaded to elements of said frame adapted to cause engagement of the friction elements of said clutches, and means convenient to the hand of the operator adapted to rotate said thrust collars and thereby control the actuation of said friction clutches as and for the purpose set forth.

22. In a machine of the class described, the combination with a frame adapted to rest upon and slide in any direction over the floor of a mine, a kerf cutter projecting horizontally therefrom, a motor mounted upon said frame connected with said kerf cutter, feeding and guiding mechanism comprising two flexible draft elements adapted to cooperate with anchoring devices external of the machine, two winding drums rotatably mounted upon said frame adapted to wind said draft elements, power transmitting devices including two friction clutches adapted to transmit rotative power from said motor to said drums, thrust collars screw threaded to elements of said frame adapted to cause engagement of the friction elements of said clutches and control devices positioned convenient to the hand of the operator external of said frame adapted to rotate said thrust collars and thereby control the actuation of said friction clutches, as and for the purpose set forth.

23. In a mining machine, the combination with a frame adapted to be moved over a

mine floor, a motor mounted on said frame, a pair of drums mounted on said frame, a rotatable drive element for one of said drums, power connections between said motor and said drive element, and driving connections between said drive element and the other of said drums including a pawl and ratchet device.

24. In a mining machine, the combination with a frame adapted to be moved over a mine floor, a motor mounted on said frame, a pair of drums mounted on said frame, a rotatable drive element for one of said drums, power connections between said motor and said drive element for rotating the latter in either direction, and constant direction driving connections between said drive element and the other of said drums.

25. In a mining machine, the combination with a frame adapted to be moved over a mine floor, a motor mounted on said frame, a pair of drums mounted on said frame, a rotatable drive element for one of said drums and mounted in concentric relation thereto, power connections between said motor and said drive element for rotating the latter in either direction, constant direction driving connections between said drive element and the other of said drums, and clutch means between said drive element and its associated drum.

26. In a mining machine, the combination with a frame adapted to be moved over a mine floor, a motor mounted on said frame, a pair of drums mounted on said frame, a rotatable drive element for one of said drums, power connections between said motor and said drive element for rotating the latter in either direction, and pawl and ratchet transmission means between said drive element and the other drum, whereby a unidirectional drive is imparted to the latter.

27. In a machine of the class described, the combination with a frame adapted to be moved over a mine floor, of a shaft journaled in bearings on the frame, one of said shaft bearings having an external cylindrical portion provided with screw threads, an internally threaded thrust collar engaged on said cylindrical portion for reciprocation there along upon relative rotation in opposite directions, a drum adapted to be driven by said shaft, a rotary driven element coaxial with said shaft and freely rotatable relative thereto, a clutch interposed between said driven elements and said shaft and controlled by said thrust collar in its reciprocatory movements, and means to rotate said thrust collar.

28. In a machine of the class described, the combination with a frame adapted to be moved over a mine floor, of a shaft journaled in bearings on the frame, one of said shaft bearings having an external cylindrical portion provided with screw threads, an internally threaded thrust collar engaged on said

cylindrical portion for reciprocation there along upon relative rotation in opposite directions, a drum adapted to be driven by said shaft, a rotary driven element coaxial with 5 said shaft and freely rotatable relative thereto, a friction clutch interposed between said driven elements and said shaft and controlled by said thrust collar in its reciprocatory movements, and means to rotate said thrust 10 collar.

29. In a machine of the class described, the combination with a frame adapted to be moved over a mine floor, of a pair of vertical 15 shafts journaled in bearings on the frame in side by side relation, a rotary driven element coaxial with one of said shafts and freely rotatable relative thereto, an eccentric forming a part of said driven element, a clutch operable to connect said driven elements with 20 its associated shaft, a ratchet wheel freely rotatable on the other of said shafts, a pawl actuated by said eccentric cooperable with said ratchet wheel, a clutch operable to connect said ratchet wheel with its associated 25 shaft, and drums adapted to be driven by said shafts.

30. In a machine of the class described, the combination with a frame adapted to be moved over a mine floor, of a pair of vertical 30 shafts journaled in bearings on the frame in side by side relation, a rotary element coaxial with one of said shafts and freely rotatable relative thereto, said rotary element including a worm gear and an eccentric, a worm 35 engaged with said gear to drive the rotary element, a clutch operable to connect said rotary element with its associated shaft, a ratchet wheel freely rotatable on the other of said shafts, a pawl actuated by said eccentric 40 and cooperable with said ratchet wheel, a clutch operable to connect said ratchet wheel with its associated shaft, and drums adapted to be driven by said shafts.

31. In a mining machine, a rear end construction comprising a relatively thin shoe 45 adapted to rest slidably on a mine floor, a frame element spaced above the shoe, and a pair of drums mounted directly above said shoe on vertical axes and at opposite sides of 50 the longitudinal axis of the machine, the drums being bounded upwardly and downwardly by the same horizontal planes, the lower of said planes being spaced from the shoe portions immediately below the drums 55 only sufficiently to provide free running clearance for the drums.

32. In a mining machine, a rear end construction comprising a relatively thin shoe 60 adapted to rest slidably on a mine floor, a frame element spaced above the shoe, a pair of vertical pins connecting the frame element and shoe to prevent relative displacement of the two away from each other, said pins being mounted on opposite sides of the longitudinal 65 axis of the machine, and a drum rotatable

about each of said pins directly above the shoe.

33. In a mining machine, a rear end construction comprising a relatively thin shoe 70 adapted to rest slidably on a mine floor, a frame element spaced above the shoe, a pair of vertical pins connecting the frame element and shoe and constituting tension and compression members, said pins being mounted on opposite sides of the longitudinal axis of 75 the machine, and a drum rotatable about each of said pins directly above the shoe.

34. In a mining machine, a rear end construction comprising a relatively thin shoe 80 adapted to rest slidably on a mine floor, a frame element spaced above the shoe, a pair of vertical pins connecting the frame element and shoe and constituting tension and compression members, said pins being mounted on opposite sides of the longitudinal axis of the machine, a hub mounted eccentrically on each 85 of said pins, an operating lever for each hub projecting laterally of the machine, and a drum rotatable on each of said hubs directly above the shoe.

35. In a mining machine, a rear end construction comprising a relatively thin shoe 90 adapted to rest slidably on a mine floor, a hollow frame element spaced above the shoe, a pair of vertical shafts journaled in said hollow frame element with their lower ends projecting therebelow, said shafts being disposed on opposite sides of the longitudinal axis of the machine, a drum positioned below each 95 of said shafts directly above the shoe, and driving means between the shaft ends and the respective drums.

36. In a mining machine, a rear end construction comprising a relatively thin shoe 100 adapted to rest slidably on a mine floor, a hollow frame element spaced above the shoe, a pair of vertical shafts journaled in said hollow frame element with their lower ends projecting therebelow, said shafts being disposed on opposite sides of the longitudinal 105 axis of the machine, a drum positioned below each of said shafts directly above the shoe, internal teeth on the drums, and teeth on said projecting shaft ends adapted to engage the respective drum teeth.

37. In a mining machine, a rear end construction comprising a relatively thin shoe 110 adapted to rest slidably on a mine floor, a frame element spaced above said shoe, a pair of drums mounted directly above said shoe on vertical axes and at opposite sides of the longitudinal axis of the machine, a pair of vertical shafts journaled in the frame element, means including frictional clutches on the shafts above the drums for imparting rotation to said shafts, and driving connections 115 between the shafts and respective drums.

38. A mining machine comprising a supporting frame having spaced apart base and top sections, means comprising a fixed bear- 120

ing for rigidly connecting said sections against relative displacement, a rope drum, a journal bearing for said rope drum and eccentrically mounted on said fixed bearing, 5 means for driving said rope drum, and mechanism for shifting said journal bearing about said fixed bearing to render inoperative said driving means and freeing said rope drum.

10 39. A mining machine comprising frame sections spaced-apart, a fixed bearing having shoulders at its ends fitting in recesses in said frame sections to resist compression strains, means for securing the ends of said 15 bearing to said sections to resist tensional strains, a rope drum, a journal bearing for said rope drum and eccentrically mounted on said fixed bearing, driving mechanism for said rope drum, and means for shifting 20 said journal bearing to render inoperative said driving mechanism and thereby free said rope drum.

40. A mining machine comprising a feeding and guiding unit having upper and 25 lower frame sections, spaced-apart vertical bearings rigidly connecting said frame sections, a feeding rope drum and a guiding rope drum, journal bearings for said drums respectively eccentrically mounted on said 30 fixed bearings, independent means for driving said rope drums, and means for independently freeing said rope drums by independently rendering inoperative said rope drum driving means.

35 41. In a shortwall mining machine, the combination with a supporting frame, of kerf cutting mechanism mounted thereon, a feeding rope drum, a guiding rope drum, means for rotating said guiding rope drum in either direction, and power transmission mechanism connected to the feeding rope drum to always rotate the same in feeding direction irrespective of the direction of rotation of said guiding rope drum.

45 42. In a shortwall mining machine, the combination with a supporting frame, of kerf cutting mechanism mounted thereon, guiding mechanism comprising a rope drum, a motor, power transmission mechanism between said motor and said rope drum, feeding mechanism comprising another rope drum, and connections between said power transmission mechanism and said last-named rope drum to secure rotation of the latter 50 always in the same direction whether the first-named rope drum is rotated in one direction or the other.

43. In a shortwall mining machine, the combination with a frame adapted to rest on 60 and slide over a mine floor, of kerf-cutting mechanism projecting from the forward end of said frame, guiding mechanism comprising a rope drum, a reversible motor connected to said rope drum to drive the same 65 in either direction, feeding mechanism com-

prising another rope drum, and means comprising an eccentric rotatable with said first-named rope drum and connected to said feeding mechanism to secure rotation of said second-named rope drum always in the same direction irrespective of the direction of rotation of said first-named rope drum. 70

44. In a shortwall mining machine, the combination with a frame adapted to rest on and slide over a mine floor, of kerf-cutting mechanism mounted thereon, guiding mechanism comprising a rope drum, means for driving said rope drum in either direction, feeding mechanism comprising another rope drum and ratchet feeding means therefor, 75 and eccentric driving means connected between said first-named rope drum and said ratchet feeding means to secure rotation of the feeding rope drum always in the same direction irrespective of the direction of rotation of the guiding rope drum. 80

45. In a mining machine, the combination with a supporting frame adapted to rest on and slide over the mine floor, of kerf cutting mechanism on the forward end of said frame, feeding and guiding mechanism on the rear end of said frame comprising a pair of rope drums mounted for rotation on vertical axes, a motor on said frame, a single longitudinal shaft connecting said motor to said cutting mechanism and extending to a position between the axes of said rope drums, drive connections for one of said drums including intermeshing gearing of which a drive element 90 is on said shaft, and drive connections for the other of said drums driven from a driven member of said intermeshing gearing. 95

46. In a mining machine, the combination with a supporting frame adapted to rest on and slide over the mine floor, of kerf cutting mechanism on the forward end of said frame, feeding and guiding mechanism on the rear end of said frame comprising a pair of rope drums mounted for rotation on vertical axes, a motor on said frame, a single longitudinal shaft connecting said motor to said cutting mechanism and extending to a position between the axes of said rope drums, drive connections for one of said drums including intermeshing gearing of which a drive element 100 is on said shaft, and drive connections for the other of said drums including pawl and ratchet mechanism driven from a driven member of said intermeshing gearing. 105

47. In a mining machine, the combination with a supporting frame adapted to rest on and slide over the mine floor, of kerf cutting mechanism on the forward end of said frame, feeding and guiding mechanism on the rear end of said frame comprising a pair of rope drums mounted for rotation on vertical axes, a motor on said frame, a single longitudinal shaft connecting said motor to said cutting mechanism and extending to a position between the axes of said rope drums, drive con- 115 120 125 130

nections for one of said drums including intermeshing gearing of which a drive element is on said shaft, and drive connections for the other of said drums including pawl and ratchet mechanism driven from a driven member of said intermeshing gearing, each of said drive connections also including an independently operable friction clutch.

48. In a mining machine, the combination with a supporting frame adapted to rest on and slide over the mine floor, of kerf cutting mechanism on the forward end of said frame, feeding and guiding mechanism on the rear end of said frame comprising a pair of rope drums mounted for rotation on vertical axes, a motor on said frame, a single longitudinal shaft connecting said motor to said cutting mechanism and extending to a position between the axes of said rope drums, a worm on said shaft, a worm wheel driven by said worm and adapted to drive one of said drums, and mechanism driven by said worm wheel and adapted to drive the other of said drums.

49. In a mining machine, the combination with a supporting frame adapted to rest on and slide over the mine floor, of kerf cutting mechanism on the forward end of said frame, feeding and guiding mechanism on the rear end of said frame comprising a pair of rope drums mounted for rotation on vertical axes, a motor on said frame, a single longitudinal shaft connecting said motor to said cutting mechanism and extending to a position between the axes of said rope drums, a worm on said shaft, a worm wheel driven by said worm and adapted to drive one of said drums, and pawl and ratchet mechanism driven by said worm wheel and adapted to drive the other of said drums.

50. In a mining machine, the combination with a supporting frame adapted to rest on and slide over the mine floor, of kerf cutting mechanism on the forward end of said frame, feeding and guiding mechanism on the rear end of said frame comprising a pair of rope drums mounted for rotation on vertical axes, a motor on said frame, a single longitudinal shaft connecting said motor to said cutting mechanism and extending to a position between the axes of said rope drums, a worm on said shaft, a worm wheel driven by said worm and adapted to drive one of said drums, and mechanism driven by said worm wheel and adapted to drive the other of said drums, the drive for each drum including an independently operable friction clutch.

51. In a mining machine, the combination with a supporting frame adapted to rest on and slide over the mine floor, of kerf cutting mechanism on the forward end of said frame, feeding and guiding mechanism on the rear end of said frame comprising a pair of rope drums mounted for rotation on vertical axes, a motor on said frame, a single longitudinal shaft connecting said motor to said cutting

mechanism and extending to a position between the axes of said rope drums, a worm on said shaft, a worm wheel driven by said worm and adapted to drive one of said drums, and pawl and ratchet mechanism driven by said worm wheel and adapted to drive the other of said drums, the drive for each drum including an independently operable friction clutch.

In testimony whereof I have hereunto set my hand.

NILS D. LEVIN.
